UNITED STATES PATENT OFFICE.

AUGUSTE L. SALTMAN, OF NEW YORK, N. Y., ASSIGNOR, BY MESNE ASSIGNMENTS,
TO JAMES G. COFFIN, TRUSTEE.

MACHINE FOR MAKING COMPOSING-STRIPS FOR AUTOMATIC TYPOGRAPHIC APPARATUS.

1,136,083.

Specification of Letters Patent. Patented Apr. 20, 1915.

Application filed March 13, 1903. Serial No. 147,616.

To all whom it may concern:

Be it known that I, AUGUSTE L. SALTMAN, a citizen of the United States, residing at New York, in the county and State of New York, have invented a new and useful Machine for Making Composing-Strips for Automatic Typographic Apparatus, of which the following is a specification.

My invention relates to automatic typographic apparatus in which the impression or printing mechanism is controlled by means of a composing strip or ribbon. In such apparatus a strip or ribbon, usually of paper, is first marked to represent type characters, letters, words, punctuation marks, numerals, &c., the marks occupying different positions on the strip corresponding to the characters represented. When the marked strip is fed through the impression or printing apparatus its marks control the working of the same and cause it to imprint the characters signified by the marks. In other words, the printing or typographic apparatus interprets the marks and translates them into type impressions. Besides type character marks, the strip is provided with other marks which represent and control the operation of the printing apparatus, to enable it to perform spacing and other operations and generally to govern its movements.

These and other objects of the invention will in part be set forth hereinafter and in part will be obvious to those skilled in the art.

The invention consists in the novel parts, devices, mechanisms, constructions, arrangements, combinations and improvements, herein shown and described.

The accompanying drawings, referred to herein, and forming a part hereof, illustrate one embodiment of the invention, and with this specification serve to illustrate the principles of the invention.

Of the drawings: Figure 1 of those drawings shows a plan view of the machine. Figs. 1^a and 1^b are detail sectional views of the ram carriage actuating cylinder and valve mechanism Fig. 1^b being upon a larger scale. Fig. 2 is an enlarged perspective view of a portion of the upper plate of the machine, showing the ram punches and other parts mounted thereon. Fig. 2^a is a detail view of the ram carriage and stop

pins. Fig. 3 shows a side elevation of the machine, looking from the right of Fig. 1. Fig. 3^a is an enlarged sectional view of the release valve shown near the front of Fig. 1 mounted upon the base-plate 1. Fig. 4 is a section on line A—A, Fig. 1. Fig. 4^a is a broken view, partly in section, of the rear of plate 3 of the machine, showing the controller strip or ribbon and the frictional tension device for the same. Fig. 4^b is a detail view of the unit-gage. Fig. 5 is an enlarged detail view, partly in section, showing the inner end of a key lever, its engagement with the stop pins, the means for actuating one of the escapement levers, and the release mechanism for the unit counting wheel. Fig. 6 is an enlarged detail view, partly in section, showing the side elevation of the parts shown in Fig. 2. Fig. 6^a is a detail view showing the actuating means for the escapement lever shown in Fig. 6. Figs. 7 and 8 are elevation and plan views respectively on an enlarged scale of the unit storing and justifier setting mechanism, shown below plate 3 of the machine in Fig. 3. Fig. 7^a is a detail view, showing the connection of the finis key with the alarm mechanism, and also with the rack pinion. Fig. 7^b is a horizontal sectional view of the end of the unit storing rack shown in Fig. 7. Fig. 8^a is a sectional view on line x—x, Fig. 8. Fig. 8^b is a detail of the scale, and shown in Fig. 8. Fig. 8^c is a sectional view on line y—y, Fig. 8. Fig. 9 is a longitudinal sectional view of the machine on line B—B, Figs. 1 and 3. Fig. 9^a is a detail view, showing the unit wheel and connections. Figs. 10, 10^a, 10^b and 10^c are sectional and detail views illustrating the construction and operation of the ram carriage and the stop pin returning device. Fig. 11 is a broken perspective view, partly in section, showing the parts coöperating with the key levers to actuate the ram carriage and to count the units. Figs. 12 and 12^a are details illustrating the working of the shift key stop pins. Fig. 13 is a detail view of the unit wheel. Fig. 14 is a detail view, showing a modified form of construction for operating the escapement lever shown in Figs. 5 and 6^a. Fig. 15 is a detail end view in elevation, showing the shift keys and their connections. Fig. 16 is a sectional view on line x—x of Fig. 15. Fig. 17

is a section on line *z*—*z*, Fig. 15, with the valves and valve stems removed. Fig. 18 is a perspective sectional view of the valve box, shown in Figs. 15 and 17, on line *v*—*v*. Fig. 19 is an end view of the face of the plunger chamber shown in Figs. 15 and 16. Fig. 20 is the vertical cover plate for the vertical portion of the air channels shown in Fig. 18. Fig. 21 is a detail, showing retaining means for the unit gage.

Referring to the accompanying drawings, which illustrate by way of example one embodiment of the invention, and for the present more particularly to Figs. 1, 3 and 4; 15 the machine is mounted on a suitable base, 1, above which are carried, upon suitable posts, 2—2, a main plate, 3, which, in turn, carries upon suitable posts, 4, a top plate, 5. The machine is provided (see Fig. 1) with a 20 suitable keyboard, having keys which correspond to typographic characters, and having in addition thereto special keys designated the "Line" key, "Finis" key, "Justification" key, "Space" key, and a series of 25 shift keys shown at the left of the keyboard in Fig. 1. The character keys, through suitable mechanism, hereinafter described, actuate marking devices to mark the strip with the marks which represent the several 30 typographic characters corresponding to the several character keys. The marks, in accordance with certain features of the invention are made along transverse lines of the strip and the strip is automatically fed 35 forward a line-space at a time for each new line of marks, but in other of its features the invention is applicable to controllers having the marks thereon differently arranged. The special keys, except the "justification" key, the "finis" key, also mark the 40 controlling strip with corresponding marks. The mark made in the controlling strip is shown as a perforation, and the marking devices are shown as a series of punches 45 operating through a die plate. While I prefer to employ a perforated mark, I do not, however, restrict my invention to any particular kind of mark, but may use an indented mark, or a slotted mark, and provide marking devices suited thereto.

Other features of the invention and of the present embodiment not already mentioned will be referred to later at various points in the specification.

55 For convenience in reading the specification and ease in understanding the machine, I have utilized various captions or titles for various portions of the mechanism, but it will be understood that such divisions are a 60 matter of convenience and are not restrictive in character.

Strip feeding means.—The strip or ribbon in the illustrated embodiment is fed through the machine, as shown in Figs. 2, 3, 4 and 6, 65 by means of rollers, 16 and 18, the course

of the strip being indicated by the dotted lines, Fig. 6. Roller 16 is provided with sprocket teeth, 17, which engage perforations along the margins of the strip, as shown in Fig. 4^a and insure a positive feed. 70

Roller 18 is a friction roller which keeps the ribbon or strip in contact with the feed roller 16, and insures the engagement of sprocket teeth 17, with the marginal holes of the ribbon. A channel 17^a is cut in roller 75 18 to receive sprocket teeth 17 and permit the rollers 16 and 18 to come into contact with the ribbon.

In order to keep the ribbon or strip in proper position when passing across the 80 face of the die block, and to keep it taut as it is fed through the machine, so that no wrinkling or buckling may occur, a friction drag is provided (see Figs. 4 and 4^a), consisting of a spring-pressed roller 18^a mounted below the die block or plate 5 of the machine. Said roller is supported in arms 18^b secured to a rock shaft 18^c journaled on plate 3. Springs 18^d surround the rock shaft with one end respectively bearing on 90 the arms 18^b, and the other bearing against plate 3. Roller 18^a presses the ribbon against a friction surface 18^e which consists of a bar or strip covered with billiard cloth or felt. 95

The embodied form of means for causing the strip to feed forward for a new line is shown in Figs. 6 and 11, and is as follows: On one end of sprocket roller 16 (shown in dotted lines) is a belt pulley 16^a. This pulley is driven by a belt connection with a friction pulley 200 on shaft 201 mounted on plate 3 of the machine. (See Fig. 11). A pulley 202 on the end of said shaft is connected to the source of power. The shaft 105 201 also drives the justification mechanism through suitable gearing (not shown), as in the application before referred to. On sprocket roller 16, adjacent to the belt pulley, is a toothed escapement wheel 16^b; a 110 fork-shaped escapement lever 16^c pivoted on a stud 16^d on the bracket 16^e, engages the teeth of the escapement wheel and thereby normally holds the sprocket feed roller from rotation. The escapement lever is held with 115 one prong in engagement with the escapement wheel by means of a spring, 16^f, surrounding the stud 16^d, and pressing against its other prong, as shown. The tail-piece, 16^g, of escapement lever is provided with a 120 spring latch, 16^h, of the same construction as latch 86 of a similar escapement lever, 56, shown in Figs. 5, 7 and 14, hereafter described. On the lower side of top plate 5, and adjacent to the tail-piece of the escapement lever, is a pivoted finger, 16ⁱ, in position to engage the spring latch, 16^h. This finger, 16ⁱ, is moved by means of an air-driven piston 16^j, to the stem of which it is connected. The air cylinder for said pis- 125

130

ton is attached to the lower side, the plate 5, and is supplied with air through pipe 16^a, and air cylinder 140 from source of air supply. The admission of air to pipe 16^a is controlled by valve 139, which is actuated by the carriage 10 (see Fig. 2) when it reaches the end of its travel and also as carriage stops at any shift stop pin, as hereinafter described, so that every time the carriage 10, 10 engages the stem of valve 139 air is admitted through pipe 16^a to the rear of piston 16^b, urging the same forward and carrying with it the tail-piece 16^c of the escapement lever. A spring, 16^x, is provided to return the piston and arm, 16^k, to normal position. The escapement wheel is momentarily freed and roller 16 is revolved through its belt pulley until the escapement lever again engages the escapement wheel. Arm 16^k acts as a cam 20 and insures an advance of but one tooth at a time, equivalent to a ribbon feed of one line space.

The key action.—The keys are connected to suitable lever arms, 6, (Figs. 1, 3 and 4) 25 mounted upon plate 3, and pivoted at the point 7 intermediate their ends. At the inner extremity of each key lever is mounted a spring extension, 8, (shown more clearly in Figs. 5 and 11). This spring extension 30 is situated beneath the push rods 9^a, and upon depression of a key said push rods are projected upwardly through the medium of the key lever and its spring extension, and push stop pins 9 into the path of ram carriage 10, as shown in Figs. 2^a and 4, a yielding and elastic key action is secured by the construction described and the extra motion of the key lever is taken up by said spring extension.

40 The keys and key levers, in the illustrated embodiment and in accordance with certain features of the invention, are employed to set stops in the path of a reciprocating carriage, as will be hereinafter more fully explained. 45 As embodied, the stop pins 9, (Figs. 1, 2^a and 4) except those for the shift keys, are arranged in two rows, as clearly shown in Figs. 1 and 2, the pins in each row being opposite the spaces between the pins of the 50 other row. By this arrangement the ram carriage 10 is engaged in both directions of its movement. In one direction the projected pins of one row will engage it, while on its return movement it will be engaged 55 by projected pins of the other row.

The stop pins are formed U-shape with two upwardly extending limbs, 9^b, and 9^c. (Fig. 2^a) the limb, 9^b, is provided with an enlarged end to be engaged by the stop pawls 60 on the ram carriage and arrest the same in its travel when the stop pin is projected upwardly by depression of its corresponding key. The limb 9^c of the stop pins forms a means for the return of a projected stop pin, 65 as hereinafter described. The stop pins,

being made of spring material, have friction or pressure in the apertures in which they move to remain in the position to which they are moved.

As will be seen from Figs. 2 and 4, the 70 stop pins pass through the carriage runway or guide-plate, 19. Stop bars 9^d 9^d are threaded between the limbs of the stop pins and limit their upward and downward movement—the crotch of the pin limiting 75 the former, and the shoulder of the enlarged end 9^b limiting the latter movement.

The ribbon marking mechanism.—The invention, in one of its aspects, provides a series of stationary punches and dies corresponding to the perforations to be made in the controller, and an actuating device common to all said punches and actuating them successively in accordance with the keys actuated. The invention provides further 80 in connection with such series of stationary punches and dies, a common actuator traveling along said series of punches, and successively actuating the punches selected by the keyboard. The invention provides further 85 for arresting such common traveling punch actuator by means of the stops projected from the keyboard. I provide further as such actuator a traveling interponent having the punch actuator mounted thereon 90 and means for operating said punch actuator at any point along its travel. The actuating device for the punches may conveniently be called a ram. The interponent may be traveled by any suitable means, so far as 100 concerns many features of the invention, but in accordance with one feature thereof and as embodied in the illustrated form, I provide fluid pressure means therefor, and the ram carriage in the machine illustrated 105 is actuated by air pressure supplied to a suitable piston 11, reciprocating in its piston 184, described in detail at a later point (Figs. 1^a, 1, 2 and 9), and is thereby caused to travel transversely across the machine 110 above the lines of the stop pins. By the key action, stop pins corresponding to the key depressed are projected into the path of, and arrest, the carriage at corresponding points in its travel.

The stationary punches of the series is each reciprocably mounted in line with its die, the punches being spring restored after actuation. These punches (Figs. 1, 2, 4 and 6) are carried in apertures in suitable guide 120 plates 14, 14^a upon plate 5 of the machine. Each punch is provided with a coiled spring 13, working between the face of the apertured member 14 and a collar 13^a fixed on the punch, the spring being compressed 125 when the punch is thrust forward into the die and afterward restoring the punch to position. The collar 13^a when the punch is restored rests against the face of the apertured plate 14^a, thereby limiting the back- 130

ward movement of the punch to position it for action by the ram to return it to normal position after each operation. A die-plate 15^a is provided, as previously indicated with 5 a series of die-apertures corresponding to the punches. Between the rear guide 14 (Figs. 2 and 4) and the die-plate 15^a is a narrow slot 15, through which passes the controller strip to be perforated.

10 As before described, the ram carriage travels upon a suitable guide-way 19. Its construction is best shown in Figs. 1, 2, 4 and 6. It carries a ram or plunger 20, for actuating the punches successively. In the 15 embodied means for actuating the plunger 20 at the various points along its travel, the plunger is provided with a T shaped head (shown in Figs. 2 and 4) engaged by a reciprocable presser bar 22 extending along 20 the path of travel of the ram, said bar 22, having a correspondingly T shaped channel 23, in which said plunger head slides. The presser bar 22 is reciprocably mounted in suitable guides 24, at each end of said bar.

25 To the rear side of bar 22 from said channel 23, it is pivotally connected to three toggles 26. The other ends of each of said toggles is fixed to a shaft 22^a journaled in suitable 30 bearings on the machine frame. The shaft 22^a and the three toggles thus move together and give a uniform stroke or impression for the ram 20 at all points along its path of travel. In the embodied form, said bar is actuated by means of the 35 middle toggle 26, to the knuckle of which is connected a tie rod 27, (see Fig. 6). Means are provided for actuating same for each depression of a key, for which there is a corresponding punch. As embodied, 40 rod 27 passes down through an opening in top plate 5, as shown in Figs. 2, 4, 5, 6 and 11, and its lower end is connected to an intermediate point of a lever 40. The rear end of lever 40 is pivoted to the lower side 45 of top plate 5, and its front end engages a three-ribbed barrel or cage 39 on shaft 37. Each rib of the barrel rocks arm 40 to a position where the rib rolls off the arm causing its release. A spring 40^a returns lever 50 40, tie rod 27, and toggle 26 to position after each movement caused by the rotation of shaft 37. Shaft 37 is driven by means of its friction pulley 38, having belt connection with any convenient power shaft, the movement of shaft 37 being governed by the key 55 action, as will be presently explained. The depression of lever 40 by the rotation of the barrel or cage 39, straightens the toggle and thereby reciprocates bar 22, which projects the ram 20, which drives a punch 12 60 opposite which the ram is then at rest, through the ribbon or strip.

In order to remove the punchings or particles of paper punched out of the strip, a

chip or punchings box is provided as shown 65 at p, Figs. 4 and 4^a, which tapers toward its lower portion to form a conduit to conduct the punchings to any convenient waste receptacle arranged to receive them.

Upon the ram carriage is mounted a lug 70 28, (see Fig. 2) on which is pivoted a bell-crank arm 29. The downwardly projecting member of this bell-crank arm, (see Fig. 10^c) engages in an aperture 30 of the plunger 20. The horizontally extending member 75 of said bell-crank 29 is pivoted to a plunger 31, projecting downwardly through the carriage and ram 20 to engage with a rack 32, (Figs. 2^a, 10, 10^b) situated between the double line of stop pins 9. The teeth 80 of this rack are of such height as to hold the carriage until the ram has returned to a position that will allow it to clear the projecting ends of the punches. A lost motion in aperture 30 between the ram and the 85 bell-crank permits plunger 31 to lock the carriage at first advance of ram 20 and unlock it at last part of its return.

Upon the side of the carriage, (Fig. 2^a) and pivoted in lugs 33, projecting laterally 90 therefrom, are stop pawls 34, 35 the upper ends of which are engaged by spring fingers 36. Each of these stop pawls is situated directly above one of the lines of stop pins 9. Upon the upward projection of a stop pin 95 through the actuation of its key, one of the stop pawls 34 or 35, according to the direction of movement of the ram carriage, is engaged by said projected stop pin, and the carriage is arrested.

By the arrangement of two rows of stop pins and the spring-retained stop pawls on the carriage, the projected stop pins in one row arrest the carriage traveling in one direction, and the projected pins of the other 105 row arrest the carriage in the other direction. If the carriage should meet a pin in the return row before it encountered one in the "out" row, the spring-retained stop pawl allows the carriage to pass over said 110 return-row pin leaving it to be engaged on its return trip. The carriage thus engages the pins in order of sequence as it encounters them on its out and return trips. Upon the arresting of the carriage, the toggles 26 are 115 actuated on the next key stroke, projecting the ram 20, which strikes the punch opposite thereto, forcing the same through the paper and making a perforation in the strip in a position on a transverse line corresponding to the character represented by the previous key struck. At the same time the forward movement of the ram actuates the plunger 31 projecting same into engagement with the rack 32, at the same time 120 returning the projected stop to normal position by means of its return limb 9^c, which is immediately below said plunger, thereby

returning the stop pin to normal position out of the path of the stop pawls of the carriage.

It will be understood that the foregoing together with the coöperating parts and devices constitute one embodiment of "delayed action" means, that is, the perforation of the controller occurs one key stroke later than the depression of the corresponding key. This gives opportunity for correction of a very large proportion of errors in operation, as the operator is usually aware of an erroneous key stroke as soon as made, and thus opportunity of correcting it before it is marked in the controller.

The position of the carriage when arrested by a stop pin is shown in Fig. 10, where the stop pin 9 is shown as having been returned by the plunger 31 and the carriage about to assume the position shown in Fig. 10^b.

Since it often occurs that the same character is repeated and the mark for the same character always occupies the same position in a transverse line, that is transversely of the controller, means are provided to cause the mark for this repeated character to be made on a new line. In the present embodiment, with this in view, plunger 31 is allowed a slight clearance or play between the teeth of rack 32 (see Fig. 10). Upon the return of the stop pin by means of plunger 31, the carriage moves over a slight distance farther in the same direction, said movement being permitted by the above-mentioned clearance shown in Figs. 10 and 10^b between the plunger 31 and the teeth of the rack 32. Fig. 10 shows the carriage in position as arrested by a stop-pin and the plunger 31 as having just returned the stop pin. The relative positions of the stop pin and stop pawl on the carriage in this position are indicated in the view on the left in Fig. 10^a. From this position, the stop pin having been returned, the carriage moves over to the position shown in Fig. 10^b. This slight additional movement of the carriage brings the pawl 34 immediately above the stop pin, as clearly shown in Fig. 10^b and the central view of Fig. 10^a, so that if the same stop pin be actuated twice in succession, it will, upon the second actuation, free the carriage from the rack and throw up the pawl 34, as shown in view on right of Fig. 10^a, thereby permitting the carriage to proceed to the limit of its travel where it operates valve 139, as before explained, to cause a feed movement of the ribbon or strip. The carriage thus makes a complete journey before returning to the projected stop pin, and a forward feed movement of the controller strip or ribbon is thereby insured before the perforation for the repeated character is made. This results in the second perforation for the re-

peated character being made on a separate transverse line of the controller ribbon, which is necessary in order to cause the impression or typographic apparatus to duly record the repeated character.

70

Unit counting and storing mechanism.—The typographic machines usually controlled by controllers are adapted to turn out their product in justified lines. For this purpose in the controller making machine the width in the line of the successive characters, that is, their unit value, or width, must be counted and stored, and the difference between the composed line and the standard line, or line measure, must be eliminated by changing the size of the word, or interverbal, spaces. In the present machine, each key represents a plurality of characters, namely, five, there being suitable mechanism coöperating therewith to select any desired character or depression of the proper key stem. Means are therefore provided in the present embodiment for counting the width or unit value of each character put into the line, taking due account of differences in width or value of the different characters or "shifts" of any particular key. There is provided a unit gage or a member movable with the various shifts for a given key to keep the unit record in accordance with the value of the particular character selected of those belonging to the particular key. In the embodied form of such means, attached to each of the character key levers, and depending therefrom near their forward end, is an interponent 41, in the upper end of which is formed a slot which engages a pin projecting from the side of the key-lever. Surrounding said interponent is a spring 42, which allows of further movement of the key-lever after the interponent is arrested by the shelf 43, projecting from the rocking arms 44, which are pinned to rock shaft 44^a, said shelf extending the width of the keyboard below all the key levers. Mounted upon the under side of the lower plate 3, and extending across the machine and underneath the key levers. Immediately in advance of interponent, is a unit gage 45, shown detached in Fig. 4^b. This unit gage is provided with wings or vanes 45^a, each being movable into operative relation with the other parts of the unit counting mechanism to correspond with the shifts from one of the characters to another represented by a key. In the machine shown, the unit gage is represented as having five vanes corresponding to the five shift keys in the keyboard, Fig. 1. Each one of these vanes correspond to a given "face" of type; for instance, "upper case roman," "lower case roman," "upper and lower case italics" and "small caps." It is understood that the unit gage need not be limited to five vanes, but may be provided with any desired number,

75

80

85

90

100

105

110

115

120

125

130

the number of shift keys in the keyboard being increased or diminished to correspond to the number of vanes. The need for a gage having vanes corresponding to the different faces of type is occasioned by the varying number of "space units" which a given character may occupy in the different faces of type. Each vane of the shift gage is provided with notches, as shown in Fig. 4^b.
 10 These notches have depths corresponding to the space unit value of the characters they represent. Upon depression of a given key, the interponent attached thereto is depressed and is moved into the corresponding notch
 15 in the unit gage.
 Certain of the keys in the key-board, for instance, "shift," "line" and "finis" keys have no unit value, but have punches corresponding thereto. It will be apparent that
 20 when these keys are operated the unit counting and storing mechanism must not be allowed to count and store any units for these keys. For this purpose the unit gage 45 is formed to prevent the advance of the
 25 interponents 41 corresponding to these keys. Thus a stop is formed on the unit gage representing a zero unit value; the unit gage being thus prevented from advancing the unit counting and storing mechanism will be
 30 prevented from operation, as will be seen from the following: The rock arms 44 carry a bail rod 46, extending across the machine adjacent the lower ends of the interponent. The rock arms 44 are actuated from a belt-
 35 driven shaft, 46^a, through the medium of a connecting rod, 47, one end of which is attached to bail rod 46, the other end being attached to one member of a clutch, 48^a, mounted loose on shaft 46^a, hereinafter de-
 40 scribed. (See Fig. 9^a). Said shaft 46^a is provided with a friction pulley 49, (see Figs 9 and 9^a) connected by belt with a source of power. Said shaft 46^a is normally held from rotation by means of ratchet wheel
 45 60 (Figs. 3, 5 and 9^a) fast thereon, and a pawl, 50, on the end of a bell-crank lever, 51, pivoted upon a stud, 52, carried by a post, 53, upon the main plate, 1, of the machine. The other arm of the bell-crank lever
 50 51 carries a friction roller, 53^a, which engages the operative face of a cam, 54, mounted upon the belt-driven shaft 37. Cam 54 is provided with elevated and depressed portions and friction roller 53^a is held against
 55 said cam by means of spring 53^b. Pawl 50 is raised out of engagement with ratchet wheel 60 by means of the cam through the medium of the bell-crank, and is returned into engagement with the ratchet wheel by
 60 the action of spring 53^b which forces the friction roller on the bell-crank to ride into the depressed portions of the cam face.
 Ratchet wheel 60 is provided with three sets of teeth, viz., on its edge and on its two side faces, as shown in Fig. 13 of the draw-

ings. Bell-crank lever 51 is provided with a forked end in which is engaged one arm of another bell-crank lever 61 pivoted on plate 3 of the machine. The other arm of said bell-crank lever 61 engages a sleeve 62 loosely and slidably mounted on shaft 46^a. Said sleeve 62 is provided at one end with a toothed arm, 63, the tooth of which is in position to engage the crown teeth on the side of ratchet wheel 60 adjacent thereto. At its other end sleeve 62 is formed with a clutch member 48 and a collar 48^b by which it is engaged with the forked end of the bell-crank 61, as described. Clutch 48 has a pin engagement with a mating clutch member, 48^a, loosely mounted on shaft 46, but held from sliding longitudinally thereon by means of a collar 48^a, engaging a projection on bracket 48^c. Clutch members 48 and 48^a have a pin engagement 64 (see Figs. 9 and 85^a), the pins being of such a length that engagement is preserved between the members when the sleeve 62 is slid toward ratchet wheel 60, causing it to be driven by the belt pulley 49 and at the same time throws the 90 sleeve 62 and its pawl 63 into engagement with the crown teeth of the ratchet wheel 60 on the side adjacent thereto, and thereby causes said pawl and clutch members 48 and 48^a to be moved by said ratchet-wheel. Said 95 movement thrusts forward rod 47, which, in turn, rocks bail-rod 46, and carries the interponent of the depressed key into the notch of the unit gage presented to it. The extent of movement of the ratchet wheel 60 is 100 thus limited by the depth of the notch in the unit gage presented to the depressed interponent, and as the depth of the notch represents the space or number of space units occupied by the character designated by the 105 depressed key, the extent of movement of the ratchet wheel is proportional to the space unit value of the operated key. A spring 44^b, Fig. 9, surrounding rock shaft 44^a and engaging rock arm 44, returns the bail-rod 110 and connected parts to normal position.

The movement of cam 54 and its shaft 37 is controlled by the key action through the medium of a three-toothed wheel 55 fast on said shaft and an escapement lever 56 engaging therewith. (Figs. 5 and 11). Mounted to engage with said escapement wheel is a forked escapement lever 56 adapted to engage the teeth of the escapement wheel 55 and hold the same from rotation. Said escapement lever 56 is pivoted upon a stud 57, and is provided with a depending arm 58. It is normally held in engagement with one of the teeth of the escapement wheel by means of a spring 59 surrounding the stud 57, and engaging one arm thereof. Upon actuation of the escapement lever, by means hereinafter described, shaft 37 is released and free to be driven through its belt pulley 38 until the next tooth on the escapement 120 125 130

wheel is arrested by the escapement lever which has been returned to normal position by means of its spring 59, or by the arm 56^a which is struck by the teeth of the wheel 55 5 as they pass it and thereby insures the movement of the other prong of said lever into the path of the succeeding tooth of the wheel. This insures the escape of wheel 55 only one tooth at a time.

10 The escapement lever is actuated from the keys by the following mechanism: A bail-rod, 95, extends across and rests upon the ends of all the key levers, 6, and is carried by arms 94, 94^a, pinned to a rock shaft, 95^a, 15 mounted in suitable bearing brackets, 93, on plate 3 of the machine. (See Figs. 3, 4, 5 and 11). Springs 95^b on rock shaft 95^a maintain bail-rod 95 in contact with key levers 6. One of said arms—94—extends 20 beyond the bail-rod and engages valve rods 96, 97. Valve rod 97 has a slotted engagement with arm 94 and said valve-rod is made to fit friction-tight in its passage in the valve casing. To this end, a friction 25 device may be employed, as shown at 97^a. The object of the friction fit of valve rod 97 is that it will remain in whatever position to which it may be moved.

In Fig. 5 of the drawing, valves 96 and 97 30 are shown in normal position. Upon operation of a key, bail-rod 95 and arms 94, 94^a are moved upwardly. This movement raises valve 96 and thereby opens communication 35 between the source of air pressure coming from pipe 97^b and the cylinder 92. Piston 91 in said cylinder is connected with an arm, 89, fast on one end of a rock shaft, 87, which has fast on its other end a finger, 88. (See Fig. 6^a). When cylinder 92 is opened to the 40 air pressure, as described, finger 88 is rocked by its connections with piston 91 and engages the spring latch 86 in the tail-piece 58 of the escapement lever 56, which extends into the path of said finger 88. The return 45 movement of the finger 88 and piston 91 is accomplished by means of a spring, 87^a, surrounding the rock shaft bearing and pressing against finger 88.

Valve rod 97 is not affected during this 50 first movement of arm 94 by reason of its slotted engagement therewith and its friction-fit in its casing. Just before the end of its upward movement, however, arm 94 picks up valve rod 97 and thereby shuts off the air 55 supply to cylinder 92. Finger 88, and piston 91, are then returned by the action of spring 87^a to normal position. Owing to the beveled rear faces of spring latch 86 and finger 88, the latch is enabled to ride over the finger 60 on this return movement. In the meantime arm 94 has been returned to normal position by the action of spring 95^b on its rock shaft 95^a. The first portion of this return movement closes valve 96, leaving valve 97 65 in its raised position. At the last part of

the return movement arm 94 depresses valve 97 and returns it to position shown in Fig. 5, in readiness for the next key operation. By these means, piston 91 and its connections are operated only once for every complete up 70 and down movement of bail-rod 95 and arm 94.

If desired, mechanical means may be employed, instead of fluid pressure, for actuating finger 88 and escapement lever 56. I 75 have illustrated such means in Fig. 14. Rock shaft 95^a in this modification is at an intermediate point of arm 94, instead of at one end, as in the modification shown in Fig. 5. The end of arm 94, opposite to that carrying bail-rod 95 is connected by a rod 99 with one arm of a bell-crank lever, 100, pivoted on plate 3 of the machine. The other arm of bell-crank lever 100 constitutes the finger 88, which trips escapement 80 lever 56.

At each movement of the escapement lever 56 shaft 37 is free to rotate, and through the mechanism above described ratchet wheel 60 is rotated by an amount which corresponds 90 to the unit value of the character represented by the operated key. Each tooth of the ratchet wheel corresponds to one space unit, so that the unit value of a given character is represented by the number of teeth 95 passed over by toothed arm 63 in its return movement.

Unit registering or storing mechanism.—In order that the matter being composed may be divided into lines of a uniform and predetermined length, each line containing the same number of units, means are required to register or store the units occupied by each character and space, so that when the operator has filled out a line, or has so nearly 100 filled it out that only justification is required to fill it out to the predetermined length the length of the composed line may be mechanically communicated to a proper justification mechanism, whereby it may be 105 mechanically and automatically justified. The mechanism provided for registering or storing the units is as follows:—A pinion, 66, is loosely mounted on shaft 46^a (see Figs. 7, 8 and 13) adjacent ratchet wheel 60, and 110 is provided with crown teeth 68 maintained in mesh with crown teeth 69 on the ratchet wheel by means of a spring-pressed arm 71 mounted on a rock shaft 79, supported in brackets, 80, 81 rising from base plate 1 of 115 the machine. Spring 82, surrounding said rock shaft, bears against arm 71 and presses it toward ratchet wheel 60. Arm 71 has a forked lower end engaging with a sleeve, 67, formed on pinion 66; so that by means of 120 spring 82 and arm 71, pinion 66 is maintained in engagement with ratchet wheel 60 and is rotated thereby and by the same amount.

The amount of rotation given to the pinion 130

will represent the unit value of the character of the operated key, and this amount is transferred to a unit storing or registering rack, 65 (Figs. 1, 3, 7, 8, and 13) in mesh with said pinion. Said rack is mounted to slide on base plate 1 and is connected by rod 141 and arm 142 with a piston in a fluid pressure cylinder, 140, mounted below the base plate. By the rotation of the ratchet wheel as each key is operated, rack 65 is gradually moved toward the rear of the machine and against the fluid pressure in cylinder 140. It will thus be seen that the rack, by its movement, stores or registers the total unit value of the characters and spaces as they occur in the matter being composed until the limit for which the rack is set is nearly reached, when an alarm, hereinafter described, notifies the operator that the line is within a known number of units of the full line.

When the rack 65 has reached the limit of its movement for any given line, or has so nearly reached that limit that a complete word or proper division of a word cannot be included in that line, the justification mechanism is set by operation of justification lever 106, which advances a rack, 115, arranged in line with unit rack 65, until its end abuts against and is arrested by said unit rack 65. The extent of this movement of rack 115 determines the amount of justification which will be added to the line. Where rack 65 has advanced by an amount corresponding to the full unit value of the line length determined upon, rack 65 will abut against rack 115, so that the operation of justification lever 106 will produce no movement of rack and there will be no justification made.

Assuming that the justification mechanism has been set, it becomes necessary to return racks 65 and 115 to their initial position in readiness for a new line of composition. This is accomplished by the following means: The "finis" key is depressed. To the key lever of this key is attached by stud 75 a slotted arm 76 (see Figs. 7 and 7^a), the slot 77 of which is in engagement with an arm 78, projecting laterally from rock shaft 79, above described. During the movement of this key lever, the same operations are performed as are performed by the character keys, with the exception, however, that no space units are counted, the operation of this key serving merely to actuate the punch corresponding to the previously operated character key. The unit gage at the point opposite the interponent of the finis key is of such a height that there is no movement of the rod 47 and sleeve 62, and, consequently, no movement of the unit wheel 60. At the latter part of the depression of the finis key lever, the upper end of slot 77 engages arm 78 of rock shaft 79 and

swings forked arm 71 away from the ratchet wheel 60, thereby disengaging the crown teeth of the pinion 66 and ratchet wheel 60. Latch 74 thereupon snaps into engagement with pin 73 and holds the pinion away from the unit wheel. 70

Pivoted on bracket 81, which supports one end of the rock shaft 79 is a spring-pressed latch 74, in position to engage a pin 73 on an extension of arm 71. Beneath latch 74 75 is a pin 83 forming the stem of a piston contained in cylinder 84 mounted on the base-plate of the machine, and having connections 85 with a source of fluid pressure. The admission of pressure fluid through the connection 85 to cylinder 84 is controlled by means of a valve 150 in cylinder 151 supported on the base-plate of the machine. The stem of said valve 150 projects beyond its cylinder 151 in position to be engaged by rack 65, (see Figs. 3 and 3^a). The port in valve 150 is so arranged that when said valve is in its extreme left position, as shown in Fig. 3^a, communication is open through connections 85 from a fluid pressure supply to the piston 83 so that when rack 65 is in initial position, it abuts against the projecting stem of valve 150, pressing the same, against the action of spring 152, to its extreme left position, the left end of the stem or valve 150 forming a stop to limit the movement of the rack. In this initial position of rack 65 the fluid pressure communicating through connection 85 with the piston 84 throws the same upwardly, and thereby releases latch 74 from engagement with pin 73. 90 As soon as the rack moves rearwardly in the operation of the machine, the fluid pressure in cylinder 84 is cut off by the movement of valve 150, valve stem 83 consequently drops and latch 74 also drops, its movement being assisted by its spring. In this position latch 74 will engage pin 73 when the pinion is moved away from ratchet wheel 60 by the depression of the finis key, 95 as above described. Latch 74 retains the pinion 66 in disengaged position from the ratchet wheel 60, so that the action of the fluid pressure in cylinder 140 is free to return the rack 65 to its initial position. On 100 reaching that position, the end of rack 65 strikes the stem of valve 150, forcing it back until its opposite end strikes the head of cylinder 151, thus arresting rack 65 and opening the communication of connection 85 with the fluid pressure. Piston 83 is accordingly forced upwardly, releasing the loop 73 from latch 74 when the spring 82 on rock shaft 79 will return the pinion into engagement with the ratchet wheel. 105

Rack 65 is provided with an alarm mechanism to notify the operator of the approach of the end of the line. This mechanism is as follows: A metallic contact point 153 on its lower side, and a spring contact arm 154, 110

having electrical connection with an ordinary electric bell 155, is supported on the base-plate 1 of the machine at a point near the limit of movement of rack 65. The electric alarm 155 has connections as shown in Fig. 7, with an insulated stud 156 (see Fig. 7^a) fitted in plate 3 of the machine adjacent the link 76 depending from the finis key lever. A spring-pressed contact piece 157 is 5 pivotally mounted to the lower side of plate 3 in position to make contact with insulated stud 156. Said contact-piece 157 has projecting from one side thereof a pin 158 extending below but not in contact with arm 10 78 on rock shaft 79. The contact-piece 157 is maintained normally in contact with the insulated pin 156 by means of its spring 157^a, the electric circuit including the spring contact arm 154, the alarm bell, pin 156, and 15 from thence through the contact-piece 157 through the machine to the contact point 153 upon the rack 65.

When rack 65 in its rearward movement in storing the units carries its contact point 20 153 into contact with arm 154 the electric circuit is complete and the alarm rings, notifying the operator that he has approached the end of the line. He will then, after setting the justification mechanism, as above 25 indicated, operate the finis key to cause the return of the rack to its initial position. The depression of the finis key and arm 78 breaks contact between the insulated pin 156 and contact-piece 157, thereby opening the 30 circuit so that when the fluid pressure in cylinder 140 moves rack 65 backwardly, its contact point 153 in passing contact 154 does not sound the alarm because of the open circuit between contact-piece 157 and insulated 35 pin 156. Thus the alarm rings only on the rearward movement of the rack.

Rack 65 is provided with the following 40 adjustment for setting the machine to compose lines of any predetermined length: To the side of rack 65 is attached a spring leaf 45 129 provided at its end with a stud 128. A slide 126 provided with a series of perforations 127 slides between said spring leaf and the rack. Near its end rack 65 is provided 50 with a hole 130 (Fig. 7^b) registering with pin 128. For lines of shorter length, slide 126 is pulled outwardly by first raising pin 128 out of engagement with the end perforation in said slide, and the slide is adjusted to 55 the proper extent which may be conveniently indicated by means of a scale or gradations 159 marked on the base plate 1 of the machine. When the slide-piece is adjusted to the required length, stud 128 will 60 snap into the perforation in register therewith and the hole 130 in rack 65 thus holding slide piece 126 in its adjusted position.

In order that the operator may see at a 65 glance how many units are to be added to the line of justification and consequently

how much movement rack 115 will be required to be given before it will abut against rack 65, an index scale 160 (see Figs. 7, 8 and 8^b) is provided on base-plate 1 adjacent the end of movement of rack 65. The end 70 of rack 65 is provided with an index pointer 131, which moves over said scale 160 and indicates the gradation signifying the number of units which the line lacks of the uniform length. It will be understood, however, that 75 there is no computation or setting of the mechanism by the operator, as the justifying is mechanical and automatic.

Justification setting mechanism.—The machine herein described and illustrated is designed and intended to coöperate with a justification mechanism which may be similar in all its essential characteristics to the justification mechanism fully described and shown in application of Charles T. Moore 80 Ser. No. 130,459, filed Nov. 7, 1902. A description of said justification mechanism in the present application is, therefore, not necessary, and such mechanism forms no 85 part of the present invention. The connections to such or a similar justification are shown in the drawings.

Rack 116 (Figs. 3 and 7) is the rack which enters and controls the marking of the justification ribbon by releasing the punch slides 90 of the justification mechanism, as described in the former application above mentioned. Said rack 116 is actuated by the operation of justifying lever 106 as follows:—Justifying lever 106 is pinned, that is, fixed to a rock 95 shaft 104 journaled in brackets 102, 103 rising from base-plate 1. (See detail view Fig. 8^a). A stop-piece 105 is also pinned to shaft 104 and is provided with a stop-lug 107. Loosely mounted on shaft 104 is arm 108, to which is pivotally connected one end 100 of a rod 109. This rod extends to the mechanism, hereinafter described, for setting the justification mechanism. A spring 122 is loosely coiled about shaft 104 with one of 105 its ends bearing against the front edge of lever 106 and with its other end bearing against arm 108 and keeping said arm in contact with stop-lug 107. By these means, whenever the justifying lever 106 is pulled, 110 stop-piece 105 being fast on the same shaft, is moved a like amount, and spring 122 moves arm 108 to follow stop-lug 107. Spring 122 forms an elastic connection between lever 106 and arm 108, so that no 115 undue force exerted in the manual operation of said lever can be transmitted to the justification mechanism. A further advantage derived from spring 122 will be explained below. Rod 109 is pivotally connected at 120 its rear end with an arm 110 pinned to a rock shaft 112, journaled in brackets 112^a, 112^b rising from the base-plate 1. (See detail view, Fig. 8^c). A toothed sector 114 is 125 also pinned to rock shaft 112 and in mesh 130

with said sector is rack 116 which enters and controls the justification mechanism. Loosely mounted on shaft 112 is a sleeve 113 carrying a toothed sector 113^a meshing with stock-rack 115. Also carried on sleeve 113 is a ratchet wheel 117, and a spring case 125. A spring pawl 118 is mounted on the side of arm 110 and is normally held out of engagement with ratchet wheel 117 by means of a 10 cam-piece 120 on bracket 112^b, with which the tail of pawl 118 engages.

Operation of the justification lever 106, will, through connecting rod 109, move arm 110, carrying with it pawl 118, the tail of 15 which will pass out from under cam-piece 120 and the point of which will engage with ratchet wheel 117 rotating same and with it sectors 113^a and 114. These sectors are proportional the one to the other, and the advance of rack 115 is the same unit for unit 20 as rack 65, and for any movement of sector 113^a and its rack 115 a proportional movement of sector 114 and rack 116 will take place. The movements of said sectors and 25 racks are equivalent to a unit or multiples of a unit.

As above explained, the movement of rack 115 is determined by the position of rack 65. Said rack gradually approaches rack 115 30 during the operation of the machine as it stores or registers the units in a line of composed matter of the predetermined length. If the unit value of a line of composed matter should be exactly equal to the unit value 35 of the predetermined length of line for which the machine is set, rack 65 will have reached the position when its end abuts against the end of rack 115. In this case no justification will be required and no movement 40 of rack 115 or rack 116 can take place when the justification lever is operated. Said lever will have its usual movement, but this movement will be absorbed by spring 122, as explained. Thus no strain 45 will be put upon the rack, sectors or justification mechanism.

In the case where the unit value of a line 50 of composed matter is less than that of the predetermined length of line for which the machine is set, rack 65 in its final position for that line will not have reached the end of rack 115 and there will be a space left between the ends of these racks. This space will represent the number of units that line 55 lacks of the predetermined length. Movement of the justification lever 106 will, in this case, move rack 115 toward rack 65 until it is arrested thereby. Rack 116 will be moved into the justification mechanism a 60 proportional amount to cause that mechanism to make the necessary justification required.

In order to hold rack 115, and its sector 65 in advanced position, a spring pawl 121 is provided, which is pivoted to bracket 112^b so

that its point can engage ratchet wheel 117 and retain it in whatever position to which it may be moved.

In initial position pawl 121 is held out of engagement with ratchet wheel 117 by 70 means of a piston stem 123, which is arranged beneath the tail-piece of said pawl, the piston of which is actuated by fluid pressure in cylinder 124 mounted in the base plate. This cylinder has connection with the 75 source of fluid pressure through the same branch or pipe 85 as that which supplies cylinder 84 above described, and its action is governed by the same valve 150 which governs the fluid pressure in said cylinder 80 84. Thus, in the starting or initial position of rack 65, pawl 121 is held out of engagement with ratchet wheel 117. As soon as rack 65 registers the first unit value, piston stem 123 drops and pawl 121 moves to engage ratchet wheel 117, so as to hold rack 115 in advanced position when the justification lever 106 is operated.

In advancing, rack 115 winds up spring case 125, so that when justification has been 90 made and the finis key has been depressed, as before explained, and rack 65 and pinion 66 released from unit wheel 60, and the return of rack 65 by fluid pressure in cylinder 140, valve 150 is opened and fluid pressure is admitted to cylinder 124, whereupon piston stem 123 is moved upwardly, strikes tail of pawl 121, releasing it from ratchet wheel 117, whereupon spring case 125 returns rack 115 to initial position. Thus the operation 100 of the finis key returns rack 115, as well as rack 65, to initial position. Rack 116 is thrown into the justification mechanism, when lever 106 is pulled, and said rack is withdrawn by the return of lever 106. It 105 will be understood that while the lever 106 is manually actuated by the operator, this is merely a mechanical actuation, such as could be provided by automatic driving mechanism such as are provided for the other parts of the machine, if this were found desirable.

An adjustable stop or set-screw 161 is provided at the rear of base-plate 1 (see Fig. 3) to limit the return movement of rack 115 and also to adjust its initial position.

Shift mechanism.—Means are provided whereby a perforation will be made in the controller at the proper point to control the shift mechanism in the typographic machine, and means are also provided coöperating therewith for controlling the unit counting and storing mechanism. More particularly, in the present embodiment, means are provided whereby the unit gage is moved in accordance with the changes in the shift mechanism. The machine herein described and illustrated is provided with a series of shift keys to control the automatic 120 125 130

typographic apparatus with which the strip or ribbon marked by this machine is intended to coöperate, so that said typographic apparatus will select characters from the various type-faces or type-cases designated by the particular shift perforation upon the strip. The shift keys are clearly shown at the left of the keyboard in Fig. 1 of the drawings, marked *U*—*C* (upper case italics), *l*—*c* (lower case italics) *l*—*c* (lower case roman), *U*—*C* (upper case roman), *s*—*c* (small caps). These keys are provided with corresponding punches for marking perforations in the controller strip or ribbon and in the embodied form the marking mechanism is so arranged as is hereinafter described, that the shift perforation corresponding to any of these keys is placed upon a separate transverse line on the ribbon, the ribbon being automatically fed forward one transverse line-space on the operation of any of the shift keys. The means for causing said feed movement of the controlled ribbon are as follows: The stop pins corresponding to the various shift keys are of somewhat different construction from those corresponding to the character keys. Figs. 2, 12 and 12^a of the drawing show the form of these stop pins. They are provided with loosely pivoted fingers 132 on their rear faces. Upon each of these pivoted fingers is a stud 133 engaging a square aperture 134 in a slide 135 mounted to slide endwise longitudinally in the carriage guideway 19. Upon the upward projection of a shift-key stop by depression of its key, said finger 132 assumes the position shown on right of Fig. 12, projecting slightly in advance of the stop pin. The carriage being released from its previously actuated stop pin, engages said pivoted arm 132 and by means of the stud 133 thereon and its engagement with the slide 135, said carriage forces said slide endwise, (see Fig. 12^a) so as to strike an arm 136, (Fig. 2) pivotally mounted upon the top plate 5 of the machine. The carriage is brought to rest by the stop 9^b as for any other stop pin. Said arm 136 is engaged at its forward end between two depending fingers 138 on the valve stem 139, the valve of which controls the fluid pressure to the piston 16^c which actuates the escapement lever 16^e controlling the ribbon feed roll 16 thereby causing an escapement of said roller and a forward feed of the ribbon or strip one transverse line-space. The carriage will, after being arrested by shift-key stop pin, proceed to the limit of its travel before encountering any other stop pin, since the shift key stop pins are arranged as shown, near the end of its travel. The escapement lever will therefore again be actuated to cause another feed movement of the controller ribbon by the carriage striking valve stem 139. Any character

stop pin encountered by the carriage on its return movement after striking valve stem 139 will therefore have its corresponding perforation made upon a new transverse line.

As above explained, the unit-gage 45 is provided with five vanes corresponding to the five shift keys. The notches of each vane represent the unit values of the characters in each type case or shift.

The following mechanism, (Figs. 1, 3, 4, 15 to 21) is provided to move the vane corresponding to the projected shift key into position to be engaged by the interponents: The unit-gage has its ends journaled in suitable brackets on plate 1 of the machine. On one end of the gage is fast a friction driving pulley 45^x, (Figs. 1, 2 and 3), having belt connection with the source of power. Shift-key levers 6^a, 6^a, (Figs. 15 and 16) are provided with depending valve-stems 162 connected with valves 163 working in a valve box 164 supported on the base-plate 1 of the machine. Fluid pressure is admitted from the source of pressure supply to said valve box by connection 165 which connects with a common feed channel 166 in said valve box. Leading from said feed channel are five conduits 167 each of which communicates with a stop plunger 168 mounted in a circular casing 169. The conduits 167 are governed by valves 163 which pass through apertures 169^a therein so that normally said conduits are closed by said valves. When, however, a shift key is depressed, the consequent depression of its corresponding valve 163 opens communication for the fluid pressure to pass through the conduit governed by said valve to stop plunger 168 causing said plunger to be projected beyond the face of its casing 169 and to stand in the path of an arm 170 mounted on a shaft 171 formed on the end of the unit gage 45. Mounted on plate 3 of the machine is a rock-shaft 172 provided with arms 173, 173 carrying a bail-rod 174 extending to the left beyond the left arm 173 and provided at its outer end with a spring finger 175 arranged in position to engage the upper end of a pivoted latch 176 on the plunger casing 169. The lower end of said latch is yoke-shaped and engages a collar formed on clutch-piece 177. Said clutch-piece is provided with a connecting pin 179 at one end and a return pin 178 at its other end. An arm 170 is pinned to the unit-gage shaft 171 so as to rotate therewith, and is provided at one end with an aperture 170^a to receive the connecting pin 179 on clutch-piece 177. At its opposite end arm 170 moves close to the face of casing 169 so as to be intercepted by the stop plungers 168 which are projected into its path.

Upon depression of a shift key, bail-rod 180

174 is depressed, its finger 175 striking latch 176 and moving its lower yoke-shaped end inwardly carrying clutch-piece 177 toward arm 170 on the unit-gage shaft 174. By reason 5 of the pin connection 179 between the clutch-piece 177 and arm 170, return pin 178 registers with the last projected stop plunger; so that when moved inwardly as described, said pin returns the projected 10 plunger, and air is admitted by valve 163 before the pin is restored so as to insure the pin being in the path of the lever before the latter is released. At the same time fluid pressure is admitted through the channel 167 corresponding to the depressed shift key to one of the plungers 168 corresponding thereto, said plunger being projected beyond the face of casing 169. The unit gage being free to rotate upon the return of a plunger, 15 the arm 170 is rotated therewith until it is arrested by the projected plunger 168 corresponding to the depressed shift key. The gage is thus arrested in position to bring the vane corresponding to the operated shift key into position to be engaged by the inter- 20 ponents. As soon as finger 175 has passed the point of latch 176, spring 180 surrounding the shaft of the unit gage returns carrying return pin 178 free of arm 170, thus 25 permitting it to rotate, while connecting pin 179 remains in engagement with arm 170, said arm being bent outwardly as shown for that purpose. The return movement of the bail-rod 174 caused by its spring 174^a on 30 the rock-shaft 172, does not actuate arm 176 on account of the spring mounting of finger 175 which gives way as it passes the arm 176. Upon the next operation of a shift key, clutch-piece 177 is again projected inwardly 35 by the action of the finger on bail-rod 174, thereby returning stop plunger 168, last projected, by means of return pin 178, while at the same time the stop plunger 168 corresponding to the last operated shift key is 40 projected in the path of the arm 170 arresting the same in position to bring its corresponding gage-vane into proper position to coöperate with the interponents. 45

In order that the unit-gage may always 50 be brought to rest in exact position to present its vane to the interponent, a notched wheel 181, (Figs. 17 and 21), is provided on the opposite end of the unit-gage shaft in position to be engaged by a spring- 55 retaining pawl 182, the nose of which snaps into the notches of the unit wheel 181 insures the same being brought to rest in proper position, so as to present and retain the vane corresponding to the operated shift key in exact position to the inter- 60 ponents.

Carriage operating mechanism.—The carriage carrying the plunger for operating the punches is actuated by means of fluid pressure as follows: Said carriage is adjustably

connected, by means of screw-threaded and lock-nut connection, as shown, with one end of a piston rod 183 having at its other end a piston 11 moving in pressure cylinder 184 mounted on the top plate 5 of the machine. 70 Said cylinder and its valve connections are shown in Figs. 1, 1^a and 1^b. Fluid pressure is supplied to said cylinder through connection 185 and its admission and exhaust is controlled by means of a valve 186, ports 75 187, 187 and passages 188, 188, which connect respectively with the two ends of the pressure cylinder 184. Valve 186 is of the form and construction shown in Fig. 1^b, having full portions 189 which open and 80 close the entrance ports 187, 187, and cut-away portions 190 by which connection is established between the pressure supply passage 185 and the ports 187. The central full portion of valve 186 is also cut away on its 85 rear face so as to afford passage for pressure fluid, from the supply connection 185 to either of the cut-away portions 190. The chamber 191 in which said valve moves is open at each end forming exhausts for the 90 pressure fluid through exhaust ports 192 from the pressure cylinder 184 to the atmosphere. In order that the exhaust may be rapid, ports 192 are in the form of slots cut in the forward wall of the valve chamber 191, thus giving exhaust ports with a 95 large area.

Valve 186 is actuated by the same fluid pressure as actuates the piston in pressure cylinder 184, the control of said air pressure being accomplished by the movements of valve 186 controlled by the movement of the carriage itself. In order to effect the above stated results, pivoted arms 193, 193 are arranged on the top plate 5 of the machine having their forward ends arranged at the extremities of the travel of the carriage in position to be struck thereby. The rear ends of said arms are connected by tie-rod 194, (Fig. 2), which is adjustably connected, by means of a screw-threaded sleeve 195, with the stem of a valve 196, (Fig. 1^a) controlling the admission of pressure fluid to a piston 197 having its stem connected with the stem of valve 186. Pressure fluid 115 is led to piston 197 through the connection 198 from the fluid pressure supply 185. Pivoted arms 193 are friction tight on their pivots so as to remain in the position to which they are moved by the carriage. 120

Upon the carriage reaching the left extremity of its travel (with reference to Fig. 1), the pivoted arm 193 at the left is actuated by the carriage striking it, the valve 196 is moved to the right, opening communication for the fluid pressure to the right hand side of piston 197. This piston is thereby moved to the left carrying with it valve 186 which in its movement to the left opens the left air port 187 and places the left side of 125 180

the piston in pressure cylinder 184 in communication with the fluid pressure, at the same time opening the exhaust passage 192 at the right of valve chamber 191. The air pressure thus causes the carriage to be moved toward the right. When the carriage reaches the right extremity of its travel it strikes the right pivoted arm 193 and reverses the above-described positions of valves 196, piston 197 and valve 186 causing a reversal of the movement of the carriage.

The machine is operated by striking the keys corresponding to the characters desired to be represented, the key-strokes operating the marking, unit-counting and ribbon feeding mechanisms as above described. At the end of a word, "space" key 203 is struck to mark a normal word space representation on the ribbon. The "space" key also causes the feed of the justification ribbon a distance of one sprocket-hole. The feed mechanism of the justification ribbon and the justification slide uncovering mechanism is connected with the "space" key by connection 205 attached to bell-crank 204 arranged below the stem of the space key, all said connections being substantially the same as the various connections to the justifying mechanism in application Ser. No. 130,459 of Charles T. Moore. As before explained, the justification mechanism forms no part of the present invention, and is mentioned only to show how the present machine is connected therewith.

When the end of a line is reached and the alarm or signal has sounded, the operator strikes "line" key 206 so that a representation will be made in the ribbon to govern the typographic apparatus to recognize the end of a line. The operator, after striking the "line" key, operates the justification lever which, as explained, sets the justification mechanism. After setting the justification mechanism, the operator strikes the finis key which actuates the line-key punch and perforates the ribbon with the "line" perforation and restores the unit-rack and justification rack to initial position in readiness for a new line. The operator next depresses the "justification" key 207 which, through bell-crank 208 and connection 209, operates the clutch which causes the justification mechanism to operate to perforate the justification ribbon to represent the amount of justification for which it has been set. This is fully described in the application of Charles T. Moore above referred to.

By the use of the machine as above described and illustrated I am enabled to produce a controller strip or ribbon bearing representations of all necessary characters and functions used in the typographic art.

The said ribbon controls an automatic typographic machine so that it will reproduce any type characters, functions or impressions which may be represented upon the strip in the order in which the representations are arranged. A typographic machine 70 is automatically controlled to select the desired characters from the appropriate type cases to automatically produce lines of uniform length, inserting the required justification as the line is printed or impressed upon 75 a receiving surface. Paragraphing, indentation and other typographic functions represented upon the strip are also faithfully reproduced in the automatic typographic machine.

The strip or controller produced upon my machine has the various characters and functions arranged in the order in which they occur in composition and arranged along transverse lines of the strip. The 85 same character representation always occupies the same relative position in a transverse line, thus affording ready means of identifying each character representation.

By the above machine the sequence of 90 characters composed is automatically made to agree with the sequence of characters in the printing apparatus, without involving any attention from the operator. The requisite justification in order to fill out a line 95 to the proper uniform length is also automatically inserted without requiring any calculation or attention upon the part of the operator. The machine thus affords an automatic means for representing upon a 100 controller strip all necessary typographic operations and functions, and the operator is relieved from all care and attention, it being necessary only to strike the keys in proper order to compose the matter desired, the machine automatically performing 105 all other necessary functions.

It will be understood that my invention is not restricted to the precise mechanisms employed to attain the various results, but 110 that modifications may be made without departing from the spirit and scope of my invention.

Having thus described my invention, what I claim is new therein and desire to secure 115 by Letters Patent is:—

1. In a machine for making a composing strip for automatic typographic apparatus, the combination of a keyboard, a series of strip-marking devices severally corresponding to keys in the keyboard, key-actuated mechanism to select the strip-marking device corresponding to the actuated key, and automatic means to operate the selected strip-marking device only.

2. In a machine for making a composing strip for automatic typographic apparatus, the combination of a keyboard, a series of perforating devices corresponding to keys in the keyboard, key-controlled mechanism to 130

select the perforating device corresponding to the actuated key, and means actuated by the key next depressed to operate the selected perforating device.

5 3. In a machine for making a composing strip for automatic typographic apparatus, the combination of a keyboard, a series of strip-marking devices corresponding to keys in the keyboard, means traveling adjacent 10 said strip-marking devices for actuating the same, key-operated means to arrest said actuating means at a point corresponding to the operated key, and mechanism to cause said traveling means to actuate the strip-marking devices.

4. In a machine for making a composing strip for automatic typographic apparatus, the combination of a keyboard, a series of strip-marking devices corresponding to keys 20 in the keyboard, a traveling interponent moving adjacent the strip-marking devices, key-operated means for selecting the marking devices and arresting said traveling interponent, and means controlled by the key 25 action to cause said interponent to actuate the marking devices.

5. In a machine for making a composing strip for automatic typographic apparatus, the combination of a keyboard, a series of 30 strip-marking devices corresponding to keys in the keyboard, a traveling interponent moving adjacent the strip-marking devices, key-operated means for selecting the marking devices and arresting said traveling 35 interponent, and means controlled by the key-action to actuate the selected marking device and to release said interponent from its arrest.

6. In a machine for making a composing 40 strip for automatic typographic apparatus, the combination of a keyboard, a series of strip-marking devices corresponding to keys in the keyboard, a traveling interponent moving adjacent the strip-marking devices, 45 key-operated means for selecting the marking devices and arresting said traveling interponent adjacent the selected marking device, means actuated by the next key action to cause the interponent to operate the 50 marking device adjacent thereto and to release said interponent from arrest.

7. In a machine for making a composing strip for automatic typographic apparatus, the combination of a series of fixed punches, 55 and dies, an interponent traveling adjacent thereto, means to select one of said punches and dies and to arrest said interponent opposite to the punch and die selected, and key-controlled fluid-pressure means to actuate 60 said interponent and the selected punch.

8. In a machine for making a composing strip for automatic typographic apparatus, the combination of a series of fixed punches and dies, an interponent traveling adjacent

thereto, means to select one of said punches 65 and dies and to arrest said interponent opposite to the punch and die selected, a presser-bar adjacent the path of the interponent for actuating the same, and key-controlled fluid-pressure means for operating 70 said presser-bar.

9. In a machine for making a composing strip for automatic typographic apparatus, the combination of a keyboard, a series of strip-marking devices corresponding to keys 75 in the keyboard, guides adjacent said strip-marking devices, a carriage mounted to slide in said guides, said carriage provided with means to operate a strip-marking device, means actuated by a key to arrest the 80 carriage in position to operate a strip-marking device, and means actuated by the key next depressed to operate the strip-marking device selected by the carriage on the previous key depression. 85

10. In a machine for making a composing strip for automatic typographic apparatus, a keyboard, a series of strip-marking devices corresponding to keys in the keyboard, a presser-bar extending the length of 90 the series of strip-marking devices, an interponent arranged to travel between the series of marking devices and the presser-bar, means for moving the interponent, means controlled by the key action to cause 95 said interponent to select a marking device, and means controlled by the key action to move said presser-bar against the interponent and cause the latter to operate the selected marking device. 100

11. In a machine for making a composing strip for automatic typographic apparatus, a keyboard, a series of strip-marking devices corresponding to keys in the keyboard, a presser-bar extending the length of the 105 series of strip-marking devices, an interponent arranged to travel between the series of marking devices and the presser-bar, means for moving the interponent, means controlled by the key action to cause said 110 interponent to select a marking device, and operating means for the presser-bar to cause the same to actuate the interponent and thereby the selected marking device, said presser-bar operating-means controlled by 115 the key action.

12. In a machine for making a composing strip for automatic typographic apparatus, a keyboard, a series of strip-marking devices corresponding to keys in the keyboard, a presser-bar extending the length of the 120 series of strip-marking devices, an interponent arranged to travel between the series of marking devices and the presser-bar, means controlled by the key action to cause 125 said interponent to select a marking device, and fluid pressure operating means for the presser-bar to cause the same to actuate the

interponent and thereby the selected marking device, said presser-bar operating-means controlled by the key action.

13. In a machine for making a composing strip for automatic typographic apparatus, key-actuated means including stationary punches to mark the composing strip with one or more typographic representations along single transverse lines thereof, means to feed the strip progressively forward for each new line of marks, and automatic means to insure the strip being fed forward for a new line of representations between repeated operations of the same key.

14. In a machine for making a composing strip for a typographic apparatus, a series of strip-marking devices, a carriage traveling adjacent said strip-marking devices and having means thereon for actuating the strip-marking devices, mechanism engaged by said carriage at the end of its travel to feed the strip forward, and means to cause said carriage to operate the strip-feeding mechanism between repetitions of the same mark or representation.

15. In a machine for making a composing strip for a typographic apparatus, stationary perforating devices, a traveling carriage, strip-feeding means actuated by the carriage at the end of its travel, a series of key-operated stop-pins along the path of the carriage and adapted to be projected into said path to arrest the carriage, means on the carriage to disengage the stop-pin therefrom while retaining the carriage substantially in its arrested position, and means actuated on a repeated projection of the same stop-pin to cause the carriage to actuate the strip-feeding means.

16. In a machine for making a composing strip for a typographic apparatus, the combination of a series of strip-marking devices, a carriage arranged to travel adjacent thereto, a rack adjacent the path of said carriage, key-actuated means to arrest said carriage, operating-means on said carriage for the strip-marking devices, means on said carriage to engage said rack and disengage said carriage-arresting means.

17. In a machine for making a composing strip for a typographic apparatus, a series of strip-marking devices, a traveling interponent to actuate the same and moving adjacent thereto, a rack adjacent the path of the interponent, key-actuated stops for said interponent, means actuated by said interponent to free the same from the stops and engage said rack and key-controlled means for operating the interponent.

18. In a machine for making a composing strip for a typographic apparatus, a traveling interponent, a rack and a series of stop-pins adjacent the path of the interponent, means to project said stop-pins into the path

of the interponent to arrest its travel, and means operated by said interponent to return said projected stop-pins and engage said rack.

19. In a machine for making a composing strip for a typographic apparatus, a series of strip-marking devices, a traveling interponent for actuating the same and moving adjacent thereto, a rack adjacent the path of the interponent, a series of key-actuated stops for said interponent corresponding to the series of strip-marking devices, means actuated by the interponent to release the same from the stops and engage the same with the rack, said rack-engagement permitting extra movement of the interponent.

20. In a machine for making a composing strip for a typographic apparatus, a traveling carriage bearing an interponent, a rack and a series of stop-pins adjacent the path of the carriage, means to project said stop-pins into the path of the carriage, pawls on said carriage to engage said stop-pins when projected, means on the carriage to return a projected stop-pin and engage said rack, said engagement permitting a slight additional movement of the carriage when the stop-pin is returned to normal position.

21. In a machine for making a composing strip for a typographic apparatus, a traveling carriage, a rack and series of stop-pins adjacent the path of the carriage, means to project said stop-pins into the path of the carriage, spring-mounted pawls on said carriage to engage projected stop-pins, an additional pawl mounted on the carriage in position to return the stop-pin and engage the rack on being actuated, the engagement of said additional pawl with the rack permitting a limited movement of the carriage to bring said additional pawl over said stop-pin.

22. In a machine for making a composing strip for a typographic apparatus, a series of strip-marking devices, a traveling interponent for actuating the same and moving adjacent thereto a rack adjacent the path of the interponent, a strip-feeding mechanism arranged in the path of the interponent to be actuated thereby, a series of strips for said interponent corresponding to the series of strip-marking devices, means actuated by the interponent to release the same from the stops and engage the same with the rack, said rack engagement allowing extra movement of the interponent to carry the same free of the released stop and permit the interponent to operate the strip-feeding mechanism between repeated operations of the same stop.

23. In a machine for making a composing strip for a typographic apparatus, a series of keys, a series of strip-marking devices, a traveling interponent moving adjacent thereto, a series of stops for the interponent op-

erated by said keys, flexible engagements between the keys and the stops to permit further movement of the keys after actuation of the stops.

5 24. In a machine for making a composing strip for a typographic apparatus, a series of keys, a series of strip-marking devices, a traveling interponent moving adjacent thereto, a series of stops for the interponent operated by said keys, spring engagements between the keys and the stops to permit further movement of the keys after actuation of the stops.

10 25. In a machine for making a composing strip for a typographic apparatus, a series of key-levers, a series of strip-marking devices, a traveling interponent moving adjacent thereto, a series of stops for the interponent operated by said key-levers, flexible engagements between the key-levers and the stops to permit further movement of the key-levers after actuation of the stops.

15 26. In a machine for making a composing strip for a typographic apparatus, a series of key-levers, a series of strip-marking devices, a traveling interponent moving adjacent thereto, a series of stops for the interponent operated by said key-levers, flexible portions on said key-levers engaging said stops whereby further movement of said key-levers is permitted after said stops are actuated.

20 27. In a machine for making a composing strip for a typographic apparatus, a series of key-levers, a series of strip-marking devices, a traveling interponent moving adjacent thereto, a series of stops for the interponent operated by said key-levers, spring-fingers on said key-levers engaging said stops whereby further movement of said key-levers is permitted after said stops are actuated.

25 28. In a machine for making a composing strip for a typographic apparatus, a key-board having keys signifying typographic characters and spaces, strip-marking devices corresponding to said keys and actuated thereby, means actuated on operation of a key to select the marking device corresponding thereto, and mechanism to count and register the unit value of the character or space signified by said operated key, and means actuated by the succeeding key operation to operate the marking device selected by the previous key operation.

30 29. In a machine for making a composing strip for a typographic apparatus, a key-board, a series of strip-marking devices, a traveling carriage adjacent the strip-marking devices, an interponent carried by said carriage, means operative on the actuation of a key to bring the carriage opposite a strip-marking device, and means operated by the key next actuated to cause the in-

terponent to actuate the strip-marking device opposite thereto.

30 30. In a machine for making a composing strip for a typographic apparatus, a key-board, a series of strip-marking devices, a traveling carriage adjacent the same, a series of stop-pins and a rack adjacent the path of the carriage, a ram mounted on the carriage to engage the strip-marking devices, a plunger mounted on the carriage to engage the rack and stop-pins, said plunger engaged by the ram and actuated thereby, key-operated means to project a stop-pin into the path of the carriage to arrest the same, power-operated means released by the action of the key next operated to actuate the ram and thereby to operate the strip-marking device, engage the plunger with the rack, restore the stop-pin, and release the carriage.

35 31. In a machine for making a composing strip for a typographic apparatus, a key-board the keys of which signify typographic characters and spaces, a unit-gage provided with stops representing the unit values of the characters and spaces signified by the keys, means controlled by the keys to count and store the unit values, and means connected with each key to coöperate with its corresponding gage stop and govern the unit-counting and storing means in accordance with the unit value represented by said stop.

32. In a machine for making a composing strip for a typographic apparatus, a key-board the keys of which signify typographic characters and spaces, a unit-gage provided with stops representing the unit values of the characters and spaces represented in the key-board, mechanism controlled by the keys for counting and storing the unit values, an interponent connected to each key to coöperate with its corresponding gage-stop and govern the counting and storing mechanism in accordance with the unit value of said stop.

33. In a machine for making a composing strip for a typographic apparatus, a series of strip-marking devices and a unit counting and storing mechanism, a key-board, the keys of which correspond to the strip-marking devices, means controlled by the keys for actuating their corresponding strip marking devices, means controlled by said keys for actuating the unit counting and storing mechanism and means controlled by certain of the keys in the key-board for preventing said unit counting and storing mechanism from operating.

34. In a machine for making a composing strip for a typographic apparatus, a key-board, strip marking devices corresponding to the keys in the key-board, some of the keys in the key-board having corre-

sponding unit values and other of the keys having no unit value, a unit-counting and storing mechanism, means controlled by both sets of keys to actuate said strip-marking devices—means controlled by the keys having unit values to operate the unit-counting and storing mechanism, and means operated by the keys having no unit value to hold said unit counting and storing mechanism from operation.

35. In a machine for making a composing strip for a typographic apparatus, a keyboard some of the keys of which have corresponding unit values and other of said keys having no unit values, a unit counting and storing mechanism, means controlled by the keys having unit values to actuate said counting and storing mechanism in accordance with the unit values of the operated keys, and means to hold said unit counting and storing mechanism from action when a key having no unit value is operated.

36. In a machine for making a composing strip for a typographic apparatus, a keyboard some of the keys of which have corresponding unit values and other of said keys having no unit value, a unit gage having stops corresponding to the unit values of the unit value keys, a unit-counting and storing mechanism, means controlled by the keys to actuate said unit-counting and storing mechanism, means actuated by the keys and coöperating with corresponding stops of the unit gage to control the operation of the unit counting and storing mechanism in accordance with said stops, the unit gage being formed to coöperate with the keys having no unit value to prevent operation of the unit counting and storing mechanism.

37. In a machine for making a composing strip for a typographic apparatus, a series of keys, a corresponding series of strip-marking devices, means controlled by the several keys to actuate the strip-marking devices, individual keys and strip-marking devices signifying a plurality of different typographic designs, and means for selecting and determining the particular design to be represented by any key.

38. In a machine for making a composing strip for a typographic apparatus, a series of keys, a corresponding series of strip-marking devices, means controlled by the several keys to actuate the strip marking devices, individual keys and strip-marking devices signifying a plurality of different typographic designs, and different unit values, and means for selecting and determining the particular design and unit value to be represented by any key.

39. In a machine for making a composing strip for a typographic apparatus, a keyboard, a unit-gage provided with a plurality of vanes corresponding to a plurality of type-faces or type-cases, each of said

vanes provided with stops representing the unit values of the characters in the corresponding type-face or type-case, means for storing the unit values of successive characters, and key-controlled means to bring 70 the corresponding vane to operative position.

40. In a machine for making a composing strip for a typographic apparatus, a keyboard, a unit-gage provided with a plurality of vanes corresponding to a plurality of type-faces or type-cases, each of said vanes provided with stops representing the unit values of the characters in the corresponding type-face or type-case, means for 80 storing the unit values of successive characters, a plurality of shift-keys corresponding to the vanes of the gage, and means controlled by the several shift-keys to bring the corresponding vane to operative position. 85

41. In a machine for making a composing strip for a typographic apparatus, a keyboard, a unit-gage provided with a plurality of vanes corresponding to a plurality of type-faces or type-cases, each of said vanes provided with stops representing the unit values of the characters in the corresponding type-face or type-case, and key-controlled fluid-pressure operated means to bring the corresponding vane to operative 95 position.

42. In a machine for making a composing strip for a typographic apparatus, a keyboard, a unit-gage provided with a plurality of vanes corresponding to a plurality of type-faces or type-cases, each of said vanes provided with stops representing the unit values of the characters in the corresponding type-face or type-case, a plurality 100 of shift-keys corresponding to the vanes of the gage, means controlled by the several shift-keys to bring the corresponding vane to operative position, and means to retain said vane in operative position.

43. In a machine for making a composing strip for a typographic apparatus, a keyboard, a unit-gage provided with a plurality of vanes corresponding to a plurality of type-faces or type-cases, each of said vanes provided with stops representing the 115 unit values of the characters in the corresponding type-face, or type-case, said gage mounted to rotate to bring its vanes to operative position, stops to arrest the rotation of said gage and position its vanes, and 120 key-controlled fluid-pressure means for actuating said stops.

44. In a machine for making a composing strip for a typographic apparatus, a keyboard, a unit-gage provided with a plurality of vanes corresponding to a plurality of type-faces or type-cases, each of said vanes provided with stops representing the unit values of the characters in the corresponding type-face or type-case, a plurality 130

of shift-keys corresponding to the vanes of the gage, said gage mounted to rotate to bring its vanes to operative position, a series of stops corresponding to the shift-keys to arrest said gage and position its vanes, and fluid-pressure means controlled by the shift-keys to actuate the stop corresponding to an operated shift-key.

45. In a machine for making a composing strip for a typographic apparatus, a key-board comprising a plurality of shift-keys signifying a plurality of type-faces or type-cases, a rotary unit-gage having a plurality of vanes corresponding to the shift-keys, a series of stops in each of said vanes representing the unit values of the characters of the corresponding type-face, a series of stops corresponding to the several type-faces to arrest the rotation of the gage and position its vanes, fluid-pressure means controlled by the several shift-keys to actuate said stops, and means operated by the several shift-keys to return a previously actuated stop.

46. In a machine for making a composing strip for a typographic apparatus, a key-board having a plurality of shift-keys representing a plurality of different type-faces, means actuated by the several shift-keys to mark the composing strip with a type-shift representation corresponding to the shift-keys, unit-counting and registering mechanism, and means operated by the several shift-keys to adjust the unit-counting and registering mechanism for the type-faces corresponding to the several shift-keys.

47. In the machine for making a composing strip for a typographic apparatus, a series of keys representing characters and spaces, a series of stops severally corresponding to the character and space-keys and representing the unit values of the characters and spaces designated by the corresponding keys, a unit counting mechanism comprising a longitudinally movable rod, means controlled by the keys to move said rod, the movements of the rod limited by the stop corresponding to the actuated key an automatic justifying mechanism, and connections between the said mechanism and the unit counting mechanism.

48. A machine for making a composing strip for a typographic apparatus, a key-board, a series of stops corresponding to the character and space-keys in the key-board and representing the unit values thereof, a unit wheel, means controlled by the keys to drive said wheel, means coöoperating with the stops to control the movement of the wheel in accordance with the unit value of the character represented by the operated key, a unit storing rod actuated by the movements of the unit wheel an automatic justifying mechanism, and connections between the said mechanism and the unit counting mechanism.

49. In a machine for making a composing strip for a typographic apparatus, a key-board having character-keys and a plurality of shift-keys representing a plurality of different type-faces, a unit counting mechanism comprising a rack, means actuated by the several shift-keys to control the movements of said rack for all the characters in the type-faces corresponding to the shift-key depressed and justifying mechanism for coöperating with the unit-counting mechanism.

50. In a machine for making a composing strip for a typographic apparatus, a series of character keys, a notched bar, the notches of which correspond to the character-keys and represent the space-unit values thereof, space-unit counting mechanism actuated upon operation of a key, and means connected with each character-key to engage the notch corresponding thereto and control the space-counting mechanism and justifying mechanism for coöperating with the unit-counting mechanism.

51. In a machine for making a composing strip for a typographic apparatus, a series of character-keys and a plurality of shift-keys; a series of notched bars, the notches of each bar corresponding to the space-unit values of the several character-keys, and the several bars corresponding to the several shift-keys, space-unit counting mechanism, means operated by a shift-key to bring its corresponding bar into operative position to control the space-unit counting mechanism and justifying mechanism for coöperating with the unit-counting mechanism.

52. In a machine for making a composing strip for a typographic apparatus, a series of character-keys and a series of shift-keys; means to mark the composing strip with character representations corresponding to the character-keys, and means to mark the strip with shift representations corresponding to the several shift-keys, space-unit counting mechanism controlled by the several character-keys, and means operated by the several shift-keys to govern the control of the character-keys so that different shift representations give same or different space-unit values to the same character representations.

53. In a machine for making a composing strip for a typographic apparatus, a series of character keys, and space-unit counting mechanism, a series of notched bars, the notches of which correspond to the several character-keys and represent the space-unit values of the corresponding character, an interponent carried by each character-key to engage its corresponding notch and also engage the space-unit counting mechanism and control its movement.

54. A machine for making a composing strip for a typographic apparatus, includ-

ing in combination a series of character keys, means to add or store the unit-values of the characters and spaces represented in the matter being composed, means for causing a particular character key to register upon the said storing means one of a plurality of unit-values, and means to adjust said unit-storing means for varying lengths of lines of composed matter.

10 55. In a machine for making a composing strip for a typographic apparatus, a movable slide or rack, means to move said slide by amounts representing the unit-values of the characters and spaces in the matter being composed, adjustable means on said slide to control its total movement in accordance with the desired length of lines of composed matter.

15 56. In a machine for making a composing strip for a typographic apparatus, a movable slide or rack, means to advance said slide by amounts representing the unit values of the characters and spaces in the matter being composed, a movable slide or rack for governing the justification of the lines of composed matter, the movement of said justification-slide controlled by the advance of the first-named slide, and means to restore both slides to initial position.

20 57. In a machine for making a composing strip for a typographic apparatus, a movable slide or rack, means to advance said slide by amounts representing the unit values of the characters and spaces in the matter being composed, means to retain said slide in advanced position, a movable slide or rack for governing the justification of the lines of composed matter, the movement of said justification-slide controlled by the advance of the first-named slide, means to retain said justification-slide at its moved position, means to release both said slide-retaining means, and means to restore both slides to initial position.

25 58. In a machine for making a composing strip for a typographic apparatus, a movable slide or rack, means to advance said slide by amounts representing the unit values of the characters and spaces in the matter being composed, means to retain said slide in advanced position, a movable slide or rack for governing the justification of the lines of composed matter, the movement of said justification-slide controlled by the advance of the first-named slide, fluid-pressure means to retain said justification-slide at its moved position, means to release both said slide-retaining means, and means to restore both slides to initial position.

30 59. In a machine for making a composing strip for a typographic apparatus, a movable slide or rack, means to advance said slide by amounts representing the unit values of the characters and spaces in the matter being composed, means to retain said

slide in advanced position, a movable slide or rack for governing the justification of the lines of composed matter, the movement of said justification-slide controlled by the advance of the first-named slide, means to retain said justification-slide at its moved position, key-controlled fluid-pressure means to release both said slide-retaining means, and means to restore both slides to initial position.

70 60. In a machine for making a composing strip for a typographic apparatus, a set of keys, mechanism actuated by said keys for making a composing strip with typographic representations, means for counting and means for storing the units of the typographic representations, mechanical means connected with the keys to actuate the strip-marking mechanism during the first part of the key-movement and actuating the unit-counting and storing means on the latter part of the key-movement.

75 61. In a machine for making a composing strip for a typographic apparatus, means to add or store the unit-values of the characters and spaces represented in the matter being composed, and manually adjustable means for limiting the movement of said unit-storing means for varying lengths of lines of composed matter.

80 62. A machine for making controllers for typographic apparatus including in combination a keyboard, a series of strip-marking devices corresponding to keys in the keyboard, key-actuated mechanism to select the strip-marking devices corresponding to the actuated key, and means for intermittently moving the strip.

85 63. A machine for making controllers for typographic apparatus including in combination a keyboard, a series of strip-marking devices corresponding to keys in the keyboard, key-actuated mechanism to select the strip-marking devices corresponding to the actuated key, and means controllable by the operator for determining whether or not the strip shall feed after the actuation of a key.

90 64. A machine for making controllers for typographic apparatus including in combination a keyboard, a series of strip-marking devices corresponding to keys in the keyboard, key-actuated mechanism to select the strip-marking devices corresponding to the actuated key, means for moving the strip, and means at the keyboard for controlling said moving means.

95 65. A machine for making composition strips for typographic apparatus including in combination a keyboard, a series of strip-marking devices corresponding to keys in the keyboard, pneumatically operated means for actuating said strip-marking devices, key-operated means for positioning said actuating means in operative relation to a marking device corresponding to a key

which has been depressed, and means for causing said actuating means to actuate the strip-marking device.

66. A machine for making controllers including in combination means for making character representations, means actuating said making means, and key-board means di-

rectly controlling said actuating means for selecting the character to be perforated.

AUGUSTE L. SALTZMAN.
